UNITED STATES PATENT OFFICE.

WILLIAM E. ANDRÉE, OF CHICAGO, ILLINOIS, ASSIGNOR TO THE AMERICAN LAUNDRY MACHINERY COMPANY, OF NORWOOD, OHIO, A CORPORATION OF OHIO.

TANDEM ATTACHMENT FOR GARMENT-PRESSES.

1,398,827.

Specification of Letters Patent. Patented Nov. 29, 1921.

Application filed November 8, 1919. Serial No. 336,574.

To all whom it may concern:

Be it known that I, WILLIAM E. ANDRÉE, a citizen of the United States, residing at Chicago, in the county of Cook and State of Illinois, have invented certain new and useful Improvements in Tandem Attachments for Garment-Presses, of which the following is a specification.

This invention relates to tandem attachments for garment presses, to wit, attachments for enabling two garment presses to be used in conjunction or associated relation with each other so that a single operator can readily manipulate two presses.

The objects of the invention are to improve the mechanism or means connecting the two presses; to provide means for readily disconnecting the presses so that they can be operated individually; to provide automatic means for releasing the pressure treadle; and to also provide mechanism of this character in which the presses can readily be placed and operated at varying angles to each other.

Further objects of the invention are in part obvious and in part will appear more in detail hereinafter.

In the drawings, Figure 1 represents a front elevation illustrating two presses interconnected according to the present invention, one press being open and the other closed; Fig. 2 is a horizontal section on the line 2—2, Fig. 1, the treadle locking and release mechanism being omitted for clearness of illustration; Fig. 3 is a detail view, partly in section, illustrating the connecting rod and universal joints; Fig. 4 is a broken out sectional elevation on the line 4—4, Fig. 2, the parts being shown with the press partly closed; Fig. 5 is a similar view, the parts being shown in the position when the press is open; and Fig. 6 is a sectional plan view on the line 6—6, Fig. 5.

A and B respectively indicate the two presses to be connected together for associated operation. These presses, so far as their individual operating mechanism is concerned, are identical, so that description of one will suffice for both. The press itself may be of any suitable or preferred construction, and in the drawings, for purposes of illustration, is shown as of the character illustrated in my copending application for garment press filed of even date herewith,

Serial No. 336,573. The press comprises a suitable frame 1 carrying a stationary garment support 2 with which co-operates an upper pressing member or head 3 carried by a swinging lever which comprises two members one of which, marked 4, is pivoted at 5 to the frame and is pivotally connected at 6 to a second member 7 having a screw connection 8 with member 4 for relative adjustment between said members. The head is elevated by a tension spring or springs 9 and is moved downwardly into pressing relation with the garment support by depressing the foot treadle 10 pivoted at 11 to the frame and connected by a link 12 to one arm 13 of a lever pivoted at 14 in the frame, the other arm 15 of said lever being connected by a link 16 to the lower end of member 7. Any other operating mechanism for producing relative motion between the pressing members would be satisfactory for use with the present invention.

As is usual in such presses suitable means is provided for locking the pressing members in pressing relation, said mechanism preferably co-operating with a part of the operating mechanism for said members, such as the pressure treadle. The mechanism shown for this purpose in the drawings is of the same construction illustrated in my copending application for release treadle for garment presses filed of even date herewith, Serial No. 336,573. Briefly described said mechanism comprises a locking lever 17 pivoted at 18 to a bracket 19 carried by the frame, the upper arm 20 of said lever being normally pressed outwardly by a compression spring 21. The lower arm of said lever is provided with a cam surface 22, a longitudinally extending surface 23, and a locking toe 24, and in front of said cam surface has an extension provided with an abutment 25. Pivoted at 26 to said lever is the release treadle 27 provided with a releasing lug 28, a stop lug 29 which co-operates with the abutment 25 and a second abutment 30 on the locking toe, and which release treadle is also provided with an upwardly extending arm 31 provided with a finger 32. On a stationary bracket or support 33 is pivoted at 34 a free motion treadle 35 normally held in its upper position by a tension spring 36 and from which free motion treadle hangs a swinging wedge

member 37. 50 indicates a roller on the locking lever and 39 a roller carried by a pin mounted on one side of the pressure treadle 10. The locking and release mechanism so far described is similar in all respects to that illustrated in my copending application herein before referred to, and its operation will be explained in connection with the explanation of the mechanism associating 10 the two presses.

To couple the two presses each locking lever 17 is provided with an arm 40 extending back into the press and connected by a link 41 with an arm 42 on a shaft 43 journaled in the machine frame. The shafts 43 of the two machines are connected by any suitable mechanism so as to rotate in unison with each other. As illustrated, these shafts are connected by a rod 44 of non-circular 15 cross section, such as square, the opposite ends of which enter non-circular openings in the universal joint members 45 provided with sleeves 46 to receive the ends of the shaft members 43 and which are made to 20 rotate with the shafts, such as by the provision of keys 47 and clamping screws 48 for securing the sleeves 46 to the shafts 43. Rod 44 is of such length that when the parts are assembled, as in Fig. 3, said rod can be 25 pushed endwise into one of the universal joint sleeves 45 so as to free its opposite end from the other universal joint to thereby enable the two presses to be disconnected, and said rod is locked and secured in place 30 when the presses are connected by a set screw 49.

In the drawings, press A is shown open and press B closed. During the closing movement of press B its roller 39 moved 40 along the cam surface 22 and vertical surface 33 until said roller passed the locking toe 24, which thereupon moved rearwardly into locking position above said roller, as shown in Fig. 1. While press B is closed 45 and the garment therein is receiving ironing pressure the operator removes the work from the open press A and applies another garment thereto. The operator then closes press A by depressing its pressure treadle 50 10. The roller 39 of press A thereupon actuates its locking lever 17 so as to swing its lower end outwardly to allow said roller to reach locking position. The swinging motion of lever 17 of press A produces similar 55 motion of the locking lever of press B, so that the roller 39 of press B is released and said press opens. Consequently when the two presses are connected closing movement of one-press releases and permits opening 60 movement of the other press.

If it is desired to operate the presses with free motion, or, in other words, to raise and lower the pressing head without locking the same in its depressed position, the free motion treadle of either or both presses is de-

pressed. The wedge of the depressed free motion treadle enters the space between the roller 50 and the frame and forces out the lower end of the locking lever 17, said free motion treadle under the influence of spring 70 36 remaining in its lower position and maintaining the locking lever in its inoperative or ineffective position. The arms 40 and the mechanism connecting the same, including the rod 44, produce similar adjustment 75 of both locking levers. With this arrangement each press is free of locking relation with the other and both presses can be operated individually but without locking effect and without any necessity of direct 80 operation of the release treadles.

If it is desired to operate the presses individually with locking effect and without associated relation the set screws 48 and 49 are loosened, the rod 44 is removed and the 8 universal joints taken off. Each press is then wholly independent of the other. Depression of the release treadle 27 causes its arm 31 to rise and the finger 32, which lies underneath the free motion treadle elevates 90 the same so as to withdraw the wedge 37 from behind the roller 50. This restores the locking lever to operative condition.

The shaft 43 of each machine preferably extends outwardly on both sides thereof, 95 as shown in Fig. 1 so that a second machine can be operatively connected to either side of a first machine. Also, two associated machines may be placed at any desired angles within approximately 45° on each side of 100 the axis of the connecting rod 44. In other words, looking at Fig. 2, where C indicates the front or operating station at each of the two presses, each press can be turned from the full line position around a vertical 105 axis 51 through the universal joint to any amount toward the dotted line position. With this range of adjustment and the additional range secured by lengthening or shortening the rod 44 almost any desired 110 relation between the presses can be secured, as will be obvious.

The universal joint connection between the two machines also does away with any necessity for accurate setting of the two 115 machines relative to each other, as the two machines can be slightly askew from a symmetrical position and can be mounted at different levels within reasonable limits.

What I claim is:—

1. In apparatus of the class described, the combination with a plurality of pressing machines, each including a movable pressing member and locking means therefor, of means positively connecting the locking means of the said machines. 120

2. In apparatus of the class described, the combination with a plurality of pressing machines, each including a movable pressing member and locking means there- 125 130

for, of means embodying a single shaft connecting the locking means of the said machines.

3. In apparatus of the class described, the combination with a plurality of pressing machines, each including a movable pressing member, locking means and release means, of means operatively connecting the locking means of the said machines, said last named means being capable of operation independently of said release means.

4. In apparatus of the class described, the combination with a plurality of pressing machines, each including a movable pressing member and locking means therefor, of means positively connecting the locking means of the said machines, and independent means provided at each machine for actuation of said locking means.

5. In apparatus of the class described, the combination with a plurality of pressing machines, each including a movable pressing member and locking means therefor, of means operatively connecting the locking means of the said machines, and including a rotating shaft having a universal joint, whereby the said machines can be located at different relations with each other.

6. In apparatus of the class described, the combination with two pressing machines, each including a movable pressing member, an operating member therefor, and a locking device for said operating member having a normal tendency toward locked position and arranged to be moved to unlocked position by closing the other machine, of means operatively connecting the locking devices of the two machines.

7. In apparatus of the class described, the combination with two pressing machines, each including a movable pressing member, an operating member therefor, and a locking device for said operating member having a normal tendency toward locked position and arranged to be moved to unlocked position by closing the other machine, of means operatively connecting the locking devices of the two machines, and including a rotating shaft having a universal joint, whereby the two machines can be located at different relations with each other.

8. In apparatus of the class described, the combination with two pressing machines, each including relatively movable pressing members and treadle mechanism therefor embodying a pressure treadle and locking means therefor, of means embodying a single shaft for connecting the treadle mechanisms of the two machines, whereby closing movement of one machine unlocks the other machine.

9. In apparatus of the class described, the combination with two pressing machines, each including a movable pressing member, an operating member therefor, and a

locking device for said operating member having a normal tendency toward locked position and arranged to be moved to unlocked position by closing the other machine, of means operatively connecting the locking devices of the two machines, including a rotating shaft having a universal joint, whereby the two machines can be located at different relations with each other, and means for rendering said locking devices ineffective.

10. In apparatus of the class described, the combination with two pressing machines, each including a movable pressing member, treadle mechanism therefor, and locking means, of a shaft coupling the mechanism of the two machines and provided with a universal joint enabling the two machines to lie at different relations with each other, and means for rendering said locking devices ineffective.

11. In apparatus of the class described, the combination with two pressing machines, each including a movable pressing member, treadle mechanism therefor, and locking means, of a shaft coupling the mechanisms of the two machines and provided with a universal joint enabling the two machines to lie at different relations with each other.

12. In apparatus of the class described, the combination with two pressing machines, each including relatively movable pressing members and treadle mechanism therefor embodying a pressure treadle and locking means therefor, of means embodying a single shaft for connecting the treadle mechanisms of the two machines, whereby closing movement of one machine unlocks the other machine, and means operable at either machine for rendering the locking means of both machines ineffective.

13. In apparatus of the class described, the combination with two pressing machines, each including a movable pressing member, a member operable at the front of the machine for actuating said pressing member, and locking means for said pressing member, a means operable at either machine for rendering the locking means of the other machine inoperative.

14. In apparatus of the class described, the combination with two pressing machines, each including a movable pressing member, a member operable at the front of the machine for actuating said pressing member, and locking means for said pressing member, of means operable at either machine for rendering the locking means of both machines inoperative.

15. In apparatus of the class described, the combination with a plurality of pressing machines, each including a movable pressing member, a member operable at the front of the machine for actuating said pressing member, and locking means for said pressing member, of means operable at one machine

for rendering the locking means of another machine inoperative, and means adapted when operated to restore the locking means to operative condition.

- 5 16. In apparatus of the class described, the combination with a plurality of pressing machines, each including a movable pressing member, a member operable at the front of the machine for actuating said pressing
10 member, and locking means for said pressing member, of means operable at any one of said machines for rendering the locking means of all machines inoperative, and means adapted when operated to restore the locking means to operative condition.

- 15 17. In apparatus of the class described, the combination with a plurality of pressing machines, each embodying relatively movable pressing members and an operating
20 member therefor, of a movable locking member for each operating member, and means connecting said locking members to move together.

- 25 18. In apparatus of the class described, the combination with a plurality of pressing machines, each embodying relatively movable pressing members, an operating member therefor, and a swinging locking member, of means operatively connecting
30 said locking members, and a release treadle pivoted to each locking member for moving the same to release position.

- 35 19. In apparatus of the class described, the combination with a plurality of pressing machines, each embodying relatively movable pressing members, an operating member therefor, and a swinging locking member, of means operatively connecting

said locking members, and a free motion treadle at each machine for moving said locking members to inoperative position.

20. In apparatus of the class described, the combination with a plurality of pressing machines, each embodying relatively movable pressing members, a treadle for operating the same, and a locking member normally held yieldingly in locking position and controlled by said treadle, of means operatively connecting the locking members of the said machines.

21. In apparatus of the class described, the combination with a plurality of pressing machines, each embodying relatively movable pressing members, a treadle for operating the same, and a locking member normally held yieldingly in locked position and controlled by said treadle, of means operatively connecting the locking members of the said machines, and a free motion treadle for moving each locking member to inoperative position.

22. In apparatus of the class described, the combination with a plurality of pressing machines, each embodying relatively movable pressing members, a treadle for operating the same, and a locking member normally held yieldingly in locked position and controlled by said treadle, of means operatively connecting the locking members of the said machines, a free motion treadle for moving each locking member to inoperative position, and means at each machine for restoring the locking members to operative condition.

In testimony whereof I affix my signature. 75
WILLIAM E. ANDRÉE.
